(57) **CLAIM**

The ornamental design for a gaming machine candle housing as shown and described.

DESCRIPTION

FIG. 1 is a perspective view from above and to the right of a gaming machine candle housing showing the design.

FIG. 2 is a perspective view from below and to the left of the gaming machine candle housing shown in FIG. 1.

FIG. 3 is a front view of the gaming machine candle housing shown in FIG. 1.

FIG. 4 is a back view of the gaming machine candle housing shown in FIG. 1.

FIG. 5 is a right side view of the gaming machine candle housing shown in FIG. 1, the left side view being a mirror image thereof.

FIG. 6 is a top view of the gaming machine candle housing shown in FIG. 1.

FIG. 7 is a bottom view of the gaming machine candle housing shown in FIG. 1; and,

FIG. 8 is a perspective view of the gaming machine candle housing shown in FIG. 1 in an operating position relative to a gaming machine.

The dashed broken lines in the drawings form no part of the claimed design. The dot-dashed broken lines in the drawings depict boundary lines the areas within which form no part of the claimed design.

1 Claim, 8 Drawing Sheets
